[57] **CLAIM**

The ornamental design for a light fixture, as shown and described.

DESCRIPTION

FIG. 1 is a perspective view taken from the front, end and bottom of the light fixture showing my new design;

FIG. 2 is an end elevation view thereof, the opposite end being a mirror image;

FIG. 3 is a top view thereof; and,

FIG. 4 is a front elevation view thereof.

The fixture is broken away in FIGS. 3 and 4 for convenience of illustration.
